UNITED STATES PATENT OFFICE.

PHILIP LANE SCOTT, OF CHICAGO, ILLINOIS, ASSIGNOR TO SUPER-DIESEL TRACTOR CORPORATION, OF LA PORTE, INDIANA, A CORPORATION OF NEW YORK.

PROCESS OF MAKING PUMPS.

Original application filed December 15, 1919, Serial No. 344,883. Divided and this application filed December 15, 1920, Serial No. 430,825. Renewed January 6, 1926.

My invention relates to improvements in process of making pumps. Among the objects of my invention are to provide a pump in which all working parts are properly lubricated and in which leakage is prevented.

Another object is to provide a pump wherein the clearances will be sufficiently minute to permit pumping to be done by piston or plunger without any packing and without disastrous leakage.

In connection with carrying out my invention, I find that preferably one of the wearing surfaces either the plunger or seat ought to be soft iron and the other of steel. At least, one ought to be harder than the other, although this is not absolutely essential.

It may be said in this connection that one reason why cast iron is satisfactory for this purpose is that even though the soft iron warps and develops in pumps lumps and distortions which engage the plunger, these irregularities are immediately worn down without sticking. If bronze were used, we would have binding of the piston as soon as any appreciable distortion has taken place. Other objects will appear from time to time in the specification.

My pump, in the form here illustrated, is particularly designed for use with direct injection hydrocarbon internal combustion engines, where high pressures are used. It may, however, be adapted to a variety of other uses, for example wherever a pump is required. One form is illustrated in section in the accompanying figure, wherein

A is a jacket impervious to oil, and in the form here illustrated, is made of steel.

B is an inner liner of such material that the oil may penetrate in it and through it, and which is of such a character that it fulfills the requirements above pointed out in connection with the close clearances and fits required. In this case, it is made of cast iron. B¹ is a bore in the liner B, and enlarged at B² to provide an oil pocket or chamber. B³ is a bore in the side of the liner B and extending through the jacket A. B⁴ is another bore in the liner B, extending through the jacket A.

C is an inlet connection, screw-threaded into the bore B⁵ of the jacket A. It has the central bore C¹ which is enlarged at C² and provided with a beveled valve seat C³ upon

which the valve C⁴ is adapted to be seated by the spring C⁵. C⁶ is a packing ring held against the sleeve C⁷ in the bore B⁵ which sleeve is beveled at C⁸ to receive the spring C⁵ and has the bore C⁹ in which the valve C¹⁰ is located. The valve C¹⁰ is adapted to be seated on the beveled valve seat C¹¹ by the spring C¹². This double valve arrangement constitutes the inlet side of the pump.

D is a discharge connection, screw-threaded into the jacket A in the bore B³. It has the central bore D¹ which terminates at one end in the beveled face D² against which the spring D³ abuts. D⁴ is a packing. D⁵ is a valve sleeve having the pocket D⁶ in which is the beveled valve seat D⁷. D⁸ is a valve adapted to be seated on the valve seat by the spring D⁹. D¹⁰ is a narrowed bore in the valve sleeve in which the valve D⁸ is positioned. D¹¹ are vanes on the valve adapted to contact the sides of the bore and to cause the proper seating and alignment of the valve.

E is a plunger having the enlarged head E¹. E² is a collar secured on the head. E³ is a spring abutting at one end against the liner B and at the other against the collar E².

The pump may be driven by any suitable means such as a cam or rocker arm, not here shown, forming no part of this invention.

There is the additional feature of lubrication due to the porous quality of the iron. It has been found in practice that the oil will work through the iron and back along the piston through its entire length. This results in a film of oil entirely surrounding the piston throughout its length and thoroughly lubricating it without the medium of any additional channels or passages.

In my apparatus, I do not know exactly what the clearances are between the plunger and the plunger seat. They range probably somewhere in the neighborhood of a ten-thousandth of an inch. The reason why I do not know what the clearances are is because the parts are made originally with practically no clearance except that necessary to make it possible to force the plunger into the seat with a pressure of from 15 lbs. up, the plunger and seat being lubricated and then reciprocated with reference one to the other and thus being lapped together with an oil tight working fit without the use of any abrasive material.

- It will be understood that this invention is particularly intended for the handling of relatively light and fluid oils where relatively high velocities are used, and it finds its greatest exemplification in feeding such oil as kerosene or perhaps even gasoline through the spray nozzle to be used with the Diesel or similar types of engine although it may be used for pumping any liquid.
- 10 It is an interesting fact in connection with this particular arrangement of pump and bearing surface, that when the pump is properly made, we have a pump in which the plunger is actually freer to reciprocate than it would be if the normal type of stuffing box were used and this characteristic is one of the essential or at least exceedingly important characteristics because it makes the pump smooth and responsive in its action.
- 15 When the plunger and the bearings are fitted as I have above suggested, their relation is such that the plunger will be suspended or centered in the seat by a very thin film of oil and this film is preferably so thin that the surface tension of the oil is sufficient to resist the shearing action resultant from the movement of the plunger with respect to the seat even though the 20 pressures are very great, and this gives us a continuous oil film so that there is a negligible frictional resistance to the movement of the plunger and it is this surface tension also which probably prevents, or is largely active in preventing any leakage between the plunger and the seat. This is sharply contrasted with any arrangement where a stuffing box is used because the stuffing box has for its characteristic that 25 it tends to break the oil film thus increasing the resistance to the movement of the plunger and also doing away with any benefit which may be obtained from the surface tension resisting the leakage.
- 30 35 40 45 It will be understood that as the pump warms up to its work it develops a sensible heat which may be variable, and as a result of this the diameter of both the plunger and the seat changes in different ratios. In order that leakage may not take place during normal operation, it is necessary that the plunger must expand more than the barrel, and therefore one of the members, either the plunger or the barrel, 50 must be capable of wearing away sufficiently to produce such a fit as will satisfy the necessary conditions of permanent operation.
- The use and operation of my invention are as follows:
- 55 60 65 When the piston is drawn out by the spring a suction is produced and the two valves on the suction side are opened by it against the pressure of their springs. By this means oil is drawn into the pumping chamber. When the piston is forced back
- in opposition to the spring, suction no longer exists within the pump and the inlet valves are seated by their respective springs. As the movement of the piston continues, pressure is created and the discharge valve is unseated by it, and the liquid is forced out through the discharge connection.
- I find that the close fits provided make leakage along the plunger practically impossible and it is a fact that a pump handling upwards of 400 cubic inches of oil per hour at pressures ranging from 3000 to 8000 lbs. per square inch, will not leak more than a few drops of oil past the plunger during an hour period. In fact there is less leakage than on any stuffing box, that could be designed for use with apparatuses such as that with which my pump is associated.
- It will be evident that while I have shown in my drawings an operative device, still many changes might be made in size, shape and arrangement of parts without departing materially from the spirit of my invention, and I wish therefore, that my drawings be regarded as in a sense diagrammatic.
- What I claim is—
1. The process of manufacturing a pump which consists in forming a cylindrical seat, and a unitary plunger of substantially the same diameter inserting the plunger in the seat and forcing it in under pressure, then reciprocating one of the parts with respect to the other until a smooth working oil-tight fit is obtained.
  2. The process of manufacturing a pump which consists in forming a cylindrical seat, and a unitary plunger of substantially the same diameter inserting the plunger in the seat and forcing it in under pressure, then reciprocating one of the parts with respect to the other until a smooth working oil-tight fit is obtained without introduction of any abrasive material.
  3. The process of manufacturing a pump which consists in forming a cylindrical seat, and a plunger of substantially the same diameter, one of them being of softer material than the other, inserting the plunger in the seat and forcing it in under pressure, then reciprocating one of the parts with respect to the other until a smooth working oil-tight fit is obtained.
  4. The process of manufacturing a pump which consists in forming a cylindrical seat and an uncompressible plunger of substantially the same diameter, inserting the plunger in the seat, forcing it in under pressure, then reciprocating one of the parts with respect to the other until a smooth working oil-tight fit is obtained.
  5. The process of manufacturing a pump which consists in forming a cylindrical seat and an uncompressible plunger of substan-

tially the same diameter, inserting the plunger in the seat, forcing it in under pressure, then reciprocating one of the parts with respect to the other until a smooth working oil-tight fit is obtained, without the introduction of any abrasive material.

6. The process of manufacturing a pump which consists in forming a cylindrical seat and an uncompressible plunger of substantially the same diameter, lubricating the parts, inserting the plunger in the seat, forcing it in under pressure, then reciprocating one of the parts with respect to the other, until a smooth working oil-tight fit is obtained.

7. The process of manufacturing a pump which consists in forming a cylindrical seat and an uncompressible plunger of substantially the same diameter, lubricating the

parts, inserting the plunger in the seat, forcing it in under pressure, then reciprocating one of the parts with respect to the other until a smooth working oil-tight fit is obtained, without the introduction of any abrasive material.

8. The process of manufacturing a pump which consists in forming a cylindrical seat, and a plunger of substantially the same diameter, the seat being of softer material than the plunger, inserting the plunger in the seat, and forcing it in under pressure, then reciprocating one of the parts with respect to the other until a smooth working oil-tight fit is obtained.

Signed at Chicago, county of Cook and State of Illinois, this tenth day of December, 1920.

PHILIP LANE SCOTT.
